UNITED STATES PATENT OFFICE.

PETER J. VANDERLINDA, OF GRAND RAPIDS, MICHIGAN, ASSIGNOR OF ONE-HALF TO EDWIN L. BOWRING, OF SAME PLACE.

DESIGN FOR A REFRIGERATOR.

SPECIFICATION forming part of Design No. 33,348, dated October 9, 1900.

Application filed July 16, 1900. Serial No. 23,839. Term of patent 14 years.

to all whom it may concern.

Be it known that I, PETER J. VANDERLINDA, a citizen of the United States, residing at Grand Rapids, in the county of Kent and State of Michigan, have invented and produced a new and original Design for a Refrigerator, of which the following is a specification, reference being had to the accompanying drawing, forming part thereof.

- 5 o As shown in the drawing, the leading or material features of my design consist of the polygonal body having a pilaster at each angle and a panel in each space between the pilasters, the polygonal heads at each end, the 5 brackets at the upper ends of each pilaster, and the plinth at the lower ends of the same.

In the drawing the figure shows but three of the sides.

A represents a panel extending from the o lower head C to the upper head C'.

B represents the pilasters, each having at the top a carved bracket E, which abuts against the head C' at the top. At the bottom of each pilaster B is a plinth-block F.

A' A' are shorter panels at the top and bottom of two sides, between which are transverse bars H H, between which is a door having a plain frame I and panels A'' A''.

G represents legs beneath the lower head C, which are carved to correspond with the carv- 30 ing on the brackets E.

It is also obvious that the design shown is applicable to wardrobes, cabinets, and various other articles of furniture as well as refrigerators.

Having thus fully described my invention, what I claim as new, and desire to secure by Letters Patent, is—

The design for a refrigerator as herein shown and described. 40

In testimony whereof I affix my signature in presence of two witnesses.

PETER J. VANDERLINDA.
